UNITED STATES PATENT OFFICE.

CHARLES SWARTZ, OF NEW YORK, N. Y.

SHARPENING DEVICE.

1,318,025.

Specification of Letters Patent.

Patented Oct. 7, 1919.

Application filed March 7, 1917. Serial No. 153,113.

To all whom it may concern:

Be it known that I, CHARLES SWARTZ, a citizen of the United States, residing at New York, in the county of Bronx and State of New York, have invented certain new and useful Improvements in Sharpening Devices, of which the following is a full, clear, and exact description, such as will enable others skilled in the art to which it appertains to make and use the same.

This invention relates to machines for sharpening edged articles such as razor blades.

One of the objects of the invention is to provide a simple and practical mechanism of the character mentioned which is capable of efficient, expeditious and economical operation.

A further object is to provide an improved sharpening machine in which a plurality of blades are simultaneously acted upon and in which the insertion and removal of the blades is facilitated.

Another object is to provide an improved machine for resharpening safety razor blades which shall be largely automatic in operation, and which is of sturdy and simple construction.

Other objects and advantages will in part be obvious and in part noted hereinafter in connection with the description of the accompanying drawing, in which—

Figure 1 is a side elevational view of the machine;

Fig. 2 is one end elevation;

Fig. 3 is the opposite end elevation;

Fig. 4 is an enlarged fragmentary view of certain parts; and

Fig. 5 is an enlarged end of the blade gripper.

The typical embodiment of the invention shown, comprises in general a longitudinal supporting base 1 on which are mounted a pair of rotatable, substantially semi-cylindrical, sharpening rolls 2, 3 in spaced parallel relation on shafts 4, 5, in turn provided with engaging pinions 6 at one end and actuated through a pulley 7 from a suitable power source, such as a motor. Intermediate and below the sharpening rolls 2, 3 there is provided a longitudinal worm shaft 8 on the frame 1, which also has an end gear 9 meshing with a pinion 10 on shaft 5, and

which is thereby caused to rotate simultaneously with the stropping elements, but preferably at reduced speed.

The articles to be sharpened, in the present instance safety razor blades, are mounted in a removable clamping holder 11 adapted for insertion in a gripper 12, in turn connected by a resilient metal sheet 13 to a carrier 14. The latter is provided on its under face with worm threads 15 complementary to the threads on the lead shaft 8, and the carrier with the blades positioned therein is adapted for longitudinal or endwise insertion in the machine (at the right in Fig. 1) at the moment when the stropping rolls 2, 3 are disposed in the relation substantially as shown in Fig. 3. Thereupon the shaft 8 engages with the threads of the blade carrier and the latter's travel longitudinally (to the left of Fig. 1) is automatically commenced and continued. This travel continues until the blades have passed beyond the stropping elements, whereupon the carrier may be removed upwardly between the shafts 4 and 5. The carrier 14 has also lateral extensions 16 which take into corresponding recesses in guides 17 mounted on the base 1 at opposite sides of the lead shaft.

During the lateral travel of the blade carrier the stropping rolls turn in opposite directions and alternately wipe over opposite sides of the spring-pressed blades in such a manner that the blades receive an oblique stroke substantially the same as the action given in manual stropping.

The rolls 2, 3 may be divided into sections, as shown in Fig. 1, whereupon a portion of the surfacing, to which the blades are initially subjected, imparts a honing action and the remainder imparts a stropping action. The rolls are, for purpose of lightness and economy in manufacture, preferably hollow, and each carries a counterweight 18 which serves to reduce vibration or unnecessary wear when the machine is operated.

A material advantage of the device also resides in the adaptability for lateral insertion and removal of the blades during operation. While the blades themselves are disposed in the common zone of rotation of the stroppers (or the overlapping area of rotation of the latter), the stroppers are so shaped with rounded corners 19 and so dis-

posed that, at predetermined intervals in the rotation thereof, free entrance is permitted for the blade insertions. Operation of the machine is thus expedited and at the same time there is no likelihood of injury to the stropping surfaces when the blades are inserted.

In order to locate the blades securely against a tendency to displacement by the wiping action of the stropping rolls, the holder 11 is made to positively coact with the blades in a manner which insures against their accidental removal. As shown in Fig. 4 for a common type of blade, the holder is formed of a spring clip provided with recesses in one wall between lateral extensions 20 adapted to engage the blades above portions of the latter of increased longitudinal dimension. For blades of other makes similar holders are provided, in that they comprise a clamp in the nature of a spring clip of a peculiar shape suitable to lock the particular blade to be operated upon. All of such holders interchangeably fit within the resiliently supported gripper 12, so that the machine as shown is adapted for operation with substantially all kinds of blades upon the mere substitution of corresponding blade holders.

It will also be understood that a plurality of the blade carriers may be used for successive and end to end insertion between the stropping rolls. In this manner a plurality of blades are expeditiously and economically sharpened at each operation, and the machine may be kept in continuous sharpening use.

The resilient mounting of the blades, which enables yielding of the latter as the respective stropping rolls contact therewith, affords a light pressure which insures effective stropping. A further advantage of the mechanism described resides in the positive timing of the stropping operation. By means of the speed ratio between the shaft 8 and the rolls, it is determined positively just how long the blades are acted upon, and each set of blades is then automatically sharpened for the same period, whereby danger of burning or otherwise injuring the blades is avoided.

Having described my invention, what I

Copies of this patent may be obtained for five cents each, by addressing the "Commissioner of Patents, Washington, D. C."

claim as new and desire to secure by Letters Patent is:

1. In a device of the character described, in combination, a pair of spaced parallel rotatable stropping elements of substantially semi-cylindrical contour and disposed oppositely, said elements being alternately rotatable through a common space, a yieldable gripper intermediate said elements and adapted for positioning a blade held thereby in said common space for alternate wiping contact by said elements, and means to feed said blade longitudinally during rotation of said elements.

2. In a device of the character described, in combination, a pair of spaced rotatable stropping rolls of substantially semi-cylindrical contour, said rolls being disposed oppositely and being alternately rotatable through a common zone or space, means for resiliently supporting a plurality of blades in said common zone or space, the parts being so designed as to permit endwise entrance of said means with blades supported thereby during rotation of said rolls, and a longitudinal worm shaft adapted to effect longitudinal travel of said means after insertion to a point where the blades carried by said means are without the space of rotation of said rolls.

3. In a device of the character described, in combination, a pair of oppositely rotatable spaced parallel stropping rolls of substantially semi-cylindrical contour, said rolls being disposed oppositely and being alternately rotatable through a common space, a carrier, a blade gripper resiliently supported thereby and adapted to position blades for alternate wiping engagement by said rolls, means to permit endwise insertion of said blade gripper between said rolls during the rotation of the latter, and means to move said carrier longitudinally with respect to said rolls and without the space of action thereof.

In testimony whereof I affix my signature, in the presence of two witnesses.

CHARLES SWARTZ
